US0D1089118S

(12) **United States Design Patent** (10) Patent No.: **US D1,089,118 S**
(45) Date of Patent: ** Aug. 19, 2025

(54) **ELECTRICAL CONNECTOR**

(71) Applicant: **Delta Electronics (Shanghai) Co., Ltd.**, Shanghai (CN)

(72) Inventors: **Hongming Li**, Shanghai (CN); **Donglin Fu**, Shanghai (CN); **Kai Dong**, Shanghai (CN)

(73) Assignee: **Delta Electronics (Shanghai) Co., Ltd.**, Shanghai (CN)

(**) Term: **15 Years**

(21) Appl. No.: **29/974,107**

(22) Filed: **Nov. 20, 2024**

Related U.S. Application Data

(62) Division of application No. 29/892,508, filed on May 18, 2023, now Pat. No. Des. 1,063,862.

(30) **Foreign Application Priority Data**

Feb. 15, 2023 (CN) 202330051902.8

(57) **CLAIM**

The ornamental design for an electrical connector as shown and described.

DESCRIPTION

FIG. 1 is a front, bottom and right side perspective view of an electrical connector showing our new design;

FIG. 2 is a rear, top and left side perspective view thereof;

FIG. 3 is a front, bottom and left side perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof; and,

FIG. 9 is a bottom plan view thereof.

1 Claim, 9 Drawing Sheets
